GARMENT HANGER

Bernard Spitz, Port Washington, N. Y.

Application June 25, 1956, Serial No. 42,016

Term of patent 7 years

(Cl. D80—8)

Fig. 1.

Fig. 2.

Fig. 3.

Fig. 1 is an elevation of one side of a garment hanger showing my new design;

Fig. 2 is an end view of the same; and

Fig. 3 is an elevation of the other side thereof.

The essential features of the design are shown in solid black lines.

I claim:

The ornamental design for a garment hanger, substantially as shown and described.
